(57) **CLAIM**

The ornamental design for convertible strap for use in connection with supporting containers, as shown and described.

DESCRIPTION

FIG. 1 is a side elevational view of the convertible strap showing my new design.

FIG. 2 is a top plan view of the convertible strap of FIG. 1. FIG. 3 is a bottom plan view of the convertible strap of FIG. 1.

FIG. 4 is a top plan view of the left hand fastener of the convertible strap of FIG. 1.

FIG. 5 is a top plan view of the right hand fastener of the convertible strap of FIG. 1.

FIG. 6 is a top, front left side perspective view of the convertible strap of FIG. 1 shown in the shoulder strap mode.

FIG. 7 is a top, front left side perspective view of the convertible strap of FIG. 1 shown being collapsed into the handle mode; and,

FIG. 8 is a top, front left side perspective view of the convertible strap of FIG. 1 shown completely collapsed into the handle mode.

The broken line showing of environment in the drawings is for illustrative purposes only and forms no part of the claimed design.
